EDWIN REYNOLDS, OF BOSTON, ASSIGNOR TO HIMSELF AND JAMES A. WOODBURY, OF WINCHESTER, MASSACHUSETTS.

Letters Patent No. 67,583, dated August 6, 1867.

IMPROVEMENT IN VALVES FOR STEAM ENGINES.

The Schedule referred to in these Letters Patent and making part of the same.

TO ALL WHOM IT MAY CONCERN:

Be it known that I, EDWIN REYNOLDS, of Boston, in the county of Suffolk, and State of Massachusetts, have invented an Improved Valve-Gear for Steam Engines; and I do hereby declare that the following, taken in connection with the drawings which accompany and form part of this specification, is a description of my invention sufficient to enable those skilled in the art to practise it.

This invention relates to an improved construction of valves, and to an arrangement of one compound cam, by which alone, in connection with the regulator, the valves at each end of the steam-cylinder are controlled in their movement as to admission and exhaust of the steam. Of the drawings—

Figure 1 shows in side elevation the cylinder of a horizontal engine with my improved valve-gear therewith connected.

Figure 2 shows the same partly in plan, and partly in horizontal section, taken in the line *z z* (see fig. 1) through the centre of the front valve-chest, while

Figures 3, 4, and 5 are perspective views of my peculiar form of valves and valve-seats.

Before describing the means by which the valves are moved, so as properly to admit the passage of the steam into and out of the cylinder, I will explain the construction of the valves and valve-seats in connection with the steam-chests, cylinder, and the inlet and exhaust pipes or passages.

At each end of the cylinder there is fixed thereunto a frusto-conical valve-seat, cast separate therefrom. One of said seats is shown in perspective alone, by itself, in fig. 4, with portions broken away to exhibit its interior construction. This seat is also shown in connection with its valve in figs. 2 and 5. It has a flange, *a*, by which it is secured to the cylinder, and a frusto-conical shell, *b*, projecting therefrom, which is closed at its small end by a head, *c*. Within this shell, about midway and crosswise of its length, is a diaphragm, *d*, separating the space enclosed by the frusto-conical shell, *b*, into two parts, one of which, the outer part, or the part *a* at the small end, I shall term the exhaust part, while the other part I shall term the steam part. From this diaphragm, and extending to the exhaust passage *e*, cored in the cylinder casting, is a pipe-like formation marked *f*, opening into the exhaust part of the valve-seat, and forming a closed passage through the steam part of the valve-seat, by and through which passage the exhaust steam finds exit from said exhaust part into the exhaust passage marked *e*. This passage *f* leaves in the steam part of the valve-seat a space which is nearly annular, and which communicates with the cored passage *g* made in the end of the cylinder, through which the steam passes both in entering and in leaving it. Through the frusto-conical shell *b* are formed ports, of suitable size, shape, and number, into the aforesaid steam and exhaust spaces enclosed in the valve-seat. In the instance illustrated in the drawings, there are three ports shown as entering each of the aforesaid spaces, and I would remark that it is advisable so to proportion the parts that the ports into the exhaust space shall be of greater area than the ports into the steam space. It is perhaps almost superfluous to remark that all parts described relating to the valve-seat, valve, and valve-chest, are duplicated at the other end of the cylinder.

The valve which operates upon the described seat is a frusto-conical shell, with its small end closed by a head to which the valve-spindle is fixed, and with its large end open, the inside of the shell of the valve fitting exactly the outside of the seat, with the edge of the large end of the valve bearing upon the flange *a* of the seat, so as to prevent the valve from being forced by the steam pressure too closely upon the valve-seat. Exhaust *D*'s or passages are made in this valve, as seen at *h h h*, and steam ports *i i i* are cut through the valve, corresponding in size, shape, and spacing with the ports into the steam space of the valve-seat. The ports in the valve-seat, into the steam and exhaust spaces therein, are arranged in pairs, each pair being in one radial plane, so that when the valve is so turned as to bring one of the exhaust *D*'s or passages *h* over any pair of ports in the valve-seat, the steam from within the cylinder can escape in the direction and manner indicated by arrows marked in red ink on the drawings. The valve and valve-seat are enclosed in a tight valve-chest, with sufficient space therein to let the steam entering from the steam pipe *j* find its way freely into any of the steam ports *i i i*, in the direction and manner indicated by the arrows marked in blue ink on the drawings. The stem *k* of the valve passes through a stuffing-box, and is provided with a suitable outside bearing, and an arm, *l*, on the stem being connected with a bar, *m*, causes partial rotations of the valve consequent upon reciprocations of the bar

m, said reciprocations being caused by the action of the compound cam before referred to, the rotations of which are obtained by toothed wheels, so as to have a positive relation to the rotation of the main shaft of the engine. This compound cam, which is seen in plan in fig. 2, operates on friction-rolls *n n'* which are journalled to the bars *m m'*, the projections from the disk or plate of said cam striking against said rolls, and act thereon as inclines to move them and the bars *m m'* toward and from the centre of the cam. These projections, with but one exception, are fixed upon the plate of the cam, the exception being the projection which so moves each valve as to close the steam ports and cut off the steam from passing into the cylinder. This projection is marked *o* in the drawings, and has a hub, *p*, which is capable of turning on a sleeve, *q*, which is raised and lowered by the action of the regulator. In this sleeve *q* there is fixed a pin which, working in an inclined slot made in the hub *p*, causes partial rotations of the part *o* of the cam. One portion of the part *o* is made concentric with the centre on which it rotates. The cam-plate *r*, the hub *p*, the sleeve *q*, and the shaft *s* are all arranged to rotate together, making one revolution to each revolution of the engine-shaft, the sleeve *q* being splined to the shaft *s*, so as to rotate with it, though free to rise and fall thereon under the influence of the regulator. This cam is positive in its action, and by its action alone are the valves at each end of the cylinder controlled and moved. To trace the action of this compound cam on either of the valves, the direction of the rotation of the cam being that indicated by the arrow marked thereon, we will follow the operation thereof on the valve at the rear end of the cylinder from the position which it has in the drawing, that being where the contents of the rear end of the cylinder are freely exhausting, as the piston moves from the front to the rear of the cylinder, with the exhaust ports of the rear valve fully open. When the incline of the cam marked 1 2 abuts against the friction-roll *n'* the bar *m'* is thereby moved toward the shaft *s*, this operating to partially rotate the valve connected therewith to the extent needed to close the exhaust ports and open the steam ports, so as to admit steam upon the piston from the rear end of the cylinder. The valve then remains open where it is placed by the point 2, as it leaves the roll *n'*, till the incline 3 4 acts on the roll *n'*, and moves the bar *m'* away from the shaft *s* sufficiently to close the open steam ports, thus cutting off the steam, and the valve remains in the position where the point 4 leaves it, with the steam cut off, till the piston arrives at about the front end of the cylinder, when the projection marked 5 strikes the roll *n'*, and, by moving the bar *m'* away from shaft *s*, opens the exhaust ports, so as to allow the exhaust of the contents of the cylinder through the rear valve; the concentric portion of *o* exposed between the points 4 and 5 not causing any movement of the valve. It will thus be seen that the closing of the exhaust ports and the opening of the steam ports is effected in rapid succession by one incline, marked 1 2, and that the closing of the ports for cutting off the steam, is effected by the incline 3 4, and that the opening of the exhaust ports is effected by the incline 5, while it will be evident that the valve at the front end of the cylinder will be similarly operated upon by the said inclines of the cam, and at the proper times.

By inspection of the drawings it will be seen that the connection of the regulator with the cut-off part *o* of the cam is such as to make the incline 3 4 approach the incline 1 2 whenever the balls of the regulator are raised by increase of speed of the engine, the operation of this change of the relative position of said inclines being to cause the valves to cut off steam sooner after the steam ports are opened by the action of the incline 1 2, and thus, by lessening the amount of steam used, to reduce the speed of the engine to its normal rate. When the regulator balls fall, consequent upon diminished speed of the engine, then the effect of such falling, it is obvious, will be to cause the incline 3 4 to approach the projection 5, this permitting the steam ports to remain open longer before the valve operates to cut off steam, and thus, by increasing the consumption of steam, the speed of the engine will be brought up to its normal rate.

I claim the construction of a valve in the form of a hollow cap provided with suitable recesses and ports or openings for passages, when arranged to work upon a suitable projecting cap as a seat, also provided with suitable ports or passages, substantially as described, said caps being preferably made conical as a provision for wear.

Also the compound cam, when constructed and arranged to operate substantially as described.
